DOLLY FOR SUPPORTING HELICOPTER AND THE LIKE

James Salisbury, 2455 23rd St.,
Santa Monica, Calif. 90405

Filed Oct. 26, 1970, Ser. No. 25,672

Term of patent 3½ years

Int. Cl. D12—02

U.S. Cl. D14—3

FIG. 1

FIG. 2

FIG. 3

FIG. 4

FIG. 5

FIG. 6

FIG. 7

FIG. 1 is a perspective view of a dolly for supporting helicopter and the like showing my new design;

FIG. 2 is an elevational view of the right side thereof;

FIG. 3 is a front elevational view thereof;

FIG. 4 is an elevational view of the left side thereof;

FIG. 5 is a rear elevational view thereof;

FIG. 6 is a top plan view thereof; and,

FIG. 7 is a bottom plan view thereof.

I claim:

The ornamental design for a dolly for supporting helicopter and the like, substantially as shown.
